APPARATUS FOR COMPACTING CONCRETE
AND THE LIKERichard A. Niekamp, Dayton, Ohio, assignor to
The Master Electric Company, Dayton, Ohio, a
corporation of Ohio

Application January 11, 1936, Serial No. 58,784

4 Claims. (Cl. 259—72)

This invention relates generally to apparatus for compacting concrete or other plastic material, and more particularly to a vibrator adapted to be submerged in the material and vibrated so as to compact it.

The invention provides a means for vibrating and compacting concrete so as to produce a dense strong product which is homogeneous in character from a mix in which the proportion of water to concrete is relatively small.

In the accompanying drawing which illustrates two embodiments of my invention,

Figure 1 is a longitudinal vertical section through a vibrator;
Figure 2 is an enlarged vertical section of a portion of the apparatus shown in Figure 1; and

Figure 3 is a longitudinal vertical section through another embodiment of the invention, parts being broken away.

Referring more particularly to the embodiment illustrated in Figures 1 and 2, the vibrator has a casing indicated generally by the reference numeral 2. The casing is formed of an upper section 3, an intermediate section 4, and a lower section 5. The lower section is connected to the intermediate section by bolts 6 extending through flanges 7 and 8 formed on the sections 5 and 4, respectively. Sealing material 9 is placed between the flanges to prevent leakage of cement into the hollow interior of the vibrator.

The lower portion of the upper casing section 3 is formed with an annular groove 10 and an outwardly extending flange 11. The upper end 35 of the intermediate section 4 is provided with an outwardly extending flange 12. The flanges 11 and 12 are spaced apart by an annular washer 13 of rubber or other resilient material. Bolts 14 extend through the flanges 11 and 12, and a rubber washer 15 is inserted around each of the bolts between the flange 12 and a metallic washer 16. Surrounding each of the bolts is a non-resilient metallic spacing sleeve 17 which contacts with the flange 11 and the washer 16. The openings 18 in the flange 12, through which the bolts and spacing sleeves extend, are somewhat larger than the diameter of the spacing sleeves so as to leave a space between the sleeves and the flange. This enables the intermediate section 4 and the lower section 5 of the casing to vibrate a limited amount relative to the upper casing section 3 without causing vibration in the upper section which contains the driving motor. The intermediate section 4 and the lower section 5, in

effect, form a single section since they are rigidly bolted together by the bolts 6.

The intermediate and lower casing sections are provided with vanes 19 extending outwardly from the body portions of the sections. In the embodiment shown, the vibrator has four of these vanes, but this number may be varied if desired. The vanes 19 at the portions adjacent the flanges 7 and 8 are of substantially the same width as the flanges. The width of the flanges, however, decreases in a direction upwardly from the flange 8 so as to provide a reduced or neck portion 20 of a diameter substantially equal to the diameter of the body portion of the intermediate section 4. The width of the flanges then increases so that in the region of the flange 12 at the upper end 15 of the intermediate casing section, the vanes 19 are of substantially the same width as the flange 12. The vanes 19 increase the efficiency of the compacting action on the concrete. The reduced or neck portion 20 provided on the vibrator by narrowing or eliminating the vanes 19 at that portion enables the concrete to close in about the vibrator at the neck portion so that vibration is imparted to the concrete radially in all directions, that is, laterally, downwardly and upwardly, thereby increasing the effectiveness of the vibrating action.

An electric motor indicated generally by the reference numeral 24 is located in the upper casing section 3. The stator 25 of the motor fits tightly within the casing section 3 and rests on an inwardly extending flange 26. Electric current is supplied to the windings 27 of the stator by means of a flexible conduit 28 which extends upwardly through a head 29 and through a coupling section 30 to which a flexible hose, not shown, may be connected. The flexible hose is provided with a handle which may be grasped by the operator, the flexible hose further decreasing 40 any transmission of vibration to the hands of the operator. The conduit 28 extends through the flexible hose to a source of electric current. Sealing means 31 is provided in the head 29 for preventing inleakage of concrete.

The drive shaft 32 of the motor armature 33 is mounted in ball bearings 34 and 35 supported, respectively, in heads 29 and 35a, the motor, bearings and electrical conductor 28 all being located in the upper casing section 3. The motor 50 or driving shaft 32 is connected to a driven or eccentric shaft 34 by means of a flexible driving connection 36. In the embodiment shown in Figures 1 and 2, this flexible driving connection is made of rubber and is provided with recesses 55

37 and 38 for receiving the shafts 32 and 34, respectively. Each of the shafts is provided with splines 39 and the shafts are molded into the flexible coupling. This provides a flexible resilient driving connection between the drive shaft and the eccentric shaft.

5 A weight 40 is mounted eccentrically on the shaft 34 so that upon rotation of the shaft the weight causes vibration of the casing sections 4 10 and 5 relative to the upper casing section 3. The eccentric shaft 34 is mounted in roller bearings 41 and 42 carried by heads 43 and 44, respectively.

15 When the driving motor is operated, the shafts 32 and 34 are rotated, causing rotation of the eccentric weight 40. This causes the casing sections 4 and 5 to vibrate in a circle relative to the upper casing section 3, this vibration being permitted due to the resilient connection between the casing sections 3 and 4. The vibration is transmitted radially in all directions due to the shape of the vanes 18. The resilient coupling and sealing means between the casing sections 3 and 4 prevents vibration being transmitted to the upper section which contains the motor and motor bearings and also prevents vibration from being transmitted to the operator.

20 The embodiment illustrated in Figure 3 is, generally speaking, similar to that just described, except that instead of employing a resilient driving connection between the driving shaft and eccentric shaft, an internal gear and pinion is employed. Also, in the embodiment shown in Figure 3, the eccentric or driven shaft is located 25 so as to be offset or out of alignment with the drive shaft. Referring to Figure 3, the casing is formed of an upper section 50, an intermediate section 51 and a lower section 52. The sections 50 and 51 are connected together by resilient coupling and sealing means 53 similar to that previously described so as to allow relative vibration between the two sections of the casing.

25 An internal gear 54a is secured to the lower end of the drive shaft 54. A pinion 55 located inside of the gear 54a and meshing with the teeth 56 of the gear is secured to the upper end of a driven or eccentric shaft 57. The eccentric shaft is mounted in roller bearings 58 and 59, and secured to the shaft intermediate these bearings 40 is an eccentric weight 60. Rotation of the eccentric weight causes vibration of the casing sections 51 and 52 relative to the upper casing section 50, as in the embodiment previously described. The pinion 55 fits loosely in the internal gear 54a so as to allow for this relative vibration 45 of the casing sections and still provide a flexible driving connection for the eccentric weight.

30 The formation of the casing in a plurality of sections provides ready access to the operating mechanism located within the casing. It has been found that where the casing is made in a plurality of sections rigidly connected together by bolts without the use of a resilient connection between the sections, the vibration is transmitted from the lower to the upper section, rapidly wearing out the bolts and causing the sections to fall apart or at least to allow leakage of cement into the interior. The resilient coupling and sealing means, particularly when employed in connection with the non-resilient spacing sleeves surrounding the bolts, provides an effective arrangement for allowing limited relative vibration between the casing sections and

35 preventing the vibration from being transmitted from one section to the other. It has been found to materially increase the life of the vibrating apparatus.

40 In the embodiment illustrated in Figure 3, I have shown the eccentric shaft 57 in an offset position relative to the drive shaft 54. This arrangement increases the vibration of the lower casing section. The offset arrangement of the eccentric shaft with respect to the drive shaft 10 may be employed not only with the internal gear and pinion driving connection illustrated in Figure 3, but may be employed also in connection with the resilient driving connection 36 illustrated in Figure 1. In this case the recesses 37 15 and 38 provided in the rubber coupling 36 are offset to receive the drive shaft and driven shaft.

45 I have illustrated and described two embodiments of my invention. It is to be understood, however, that the invention may be otherwise embodied within the scope of the following claims.

I claim:

1. Apparatus for compacting concrete and the like, comprising a casing formed of a plurality of sections, resilient coupling means connecting the sections together, a motor having a drive shaft and bearings therefor all located in one section, an eccentric shaft, bearings therefor and an eccentric weight associated with the eccentric shaft all located in another section, and a yielding driving connection between the drive shaft and the eccentric shaft, the drive shaft and eccentric shaft being out of alignment with each other.

2. Apparatus for compacting concrete and the like, comprising a casing formed of a plurality of sections, resilient coupling means connecting the sections together, a motor having a drive shaft and bearings therefor all located in one section, an eccentric shaft, bearings therefor and an eccentric weight associated with the eccentric shaft all located in another section, and an internal gear and pinion driving connection between the drive shaft and eccentric shaft, the drive shaft and eccentric shaft being out of alignment with each other.

3. Apparatus for compacting concrete and the like, comprising a casing formed of a plurality of sections having spaced apart flanges on their adjacent ends, resilient sealing means between the flanges, bolts extending through the flanges and sealing means and connecting the sections together in such manner as to allow relative movement between the sections, non-resilient spacing sleeves surrounding the bolts, and means inside the casing for causing vibration of the different sections relative to each other.

4. Apparatus for compacting concrete and the like, comprising a casing formed of a plurality of sections, said casing adapted to be submerged in the concrete, resilient coupling means connecting the sections together, a motor having a drive shaft and bearings therefor, all located in one section, an eccentric shaft, bearings therefor and an eccentric weight associated with the eccentric shaft, all located in another section, a yielding driving connection between the drive shaft and the eccentric shaft, and flexible supporting means connected to the casing whereby the section of the casing containing the motor may be submerged in the concrete.
